UNITED STATES PATENT OFFICE.

WARREN F. WOLHAUPTER, OF CHICAGO, ILLINOIS, ASSIGNOR, BY MESNE ASSIGNMENTS, TO SAMUEL E. HIBBEN, OF CHICAGO, ILLINOIS.

BRUSH.

1,161,179.

Specification of Letters Patent.

Patented Nov. 23, 1915.

Application filed February 3, 1902. Serial No. 92,269.

To all whom it may concern:

Be it known that I, WARREN F. WOLHAUPTER, a citizen of the United States, residing at Chicago, Cook county, Illinois, 5 have invented certain new and useful Improvements in Brushes, Brooms, and the like, of which the following is a specification.

My invention relates to brushes, brooms and the like and the object thereof is to provide a novel form of flexible connection between a brush head and the handle therefor, the same being the operative connection therebetween, and also to provide means for permitting of the use of interchangeable 10 brooms, brushes or the like, whereby a single handle serves to accommodate cleaning devices of different character or other cleaning devices of the same character.

The features of utility and advantage will 20 be made apparent from the description hereinafter given.

In the drawing, Figure 1 is a perspective, partly in section, of my brush or broom; Fig. 2 a transverse section of a brush 25 and its clip, illustrating a slight modification in the attachment of the spring to the clip, the handle being omitted; and Fig. 3 a detail illustrating a modified form of construction.

30 My invention includes generally a brush head, a handle and a flexible connection between the brush head and the handle.

The handle, which may be of any suitable construction, is indicated by D, the brush 35 head is indicated by A, and the flexible connection between the two by C.

The brush head, in the illustrated exemplification of my invention, includes a brush back a, bristles a' secured therein, and 40 a member B detachably secured to the back, and providing means for facilitating the removal of one brush and the substitution of another brush in the place thereof, which is of great advantage, in that it permits 45 brushes of the same kind, or of different kinds or grades of fineness, to be readily substituted one for the other. The detachable member B may be constructed as shown in Figs. 1 and 2 of sheet metal stamped to 50 the desired shape and adapted to be slipped endwise on the brush back, said member being provided with inwardly turned flanges b b' which engage longitudinal grooves in the sides of the brush back. Obviously, 55 however, the detachable member B may be

constructed of any desired material or in any desired manner or form and may be differently secured upon the brush, as desired, without departure from the spirit and scope of my invention and claims.

In order to lock and hold the member in its proper position on the brush back, suitable means are adopted, for instance, a pin b' is secured in one side of the brush back so as to engage a hole in the member, as 60 seen in Fig. 1.

The flexible connection or spring means which forms the operative connection between the handle and the brush head consists essentially of a coiled spring structure 70 C arranged transversely of the axis of the handle and longitudinally of the axis of the brush head. As shown in Fig. 1 this spring structure is formed into two coiled sections c' disposed in axial alinement. The two adjacent ends of these sections are twisted together to form a shank c and inserted into the lower end of the handle which is provided with the ferrule d and their outer 80 ends are connected with the brush head through the medium of the clip B which has the eyes b' to receive said ends. However, as is now obvious from the foregoing description, the spring structure may be composed of a single rod or wire of spring metal which at its middle part may be twisted together to form said shank, so that in such case the parts c' would constitute 85 one or more coils of a spiral spring.

This construction and arrangement of the springs serves to normally hold the handle and brush head in the normal relative position indicated in Fig. 1 of the drawing. Inasmuch as the springs form the operative 90 connection between the handle and brush head, the relative movements of the head and handle in the various directions will subject it to torsional and compression and expansion strains that tend to return the brush handle to normal relative position.

In the illustrated exemplification of my invention the flexible connection is formed of two spring sections having their inner ends twisted together to form the shank c, and their outer ends, which form the outermost loops of the coils, engage with eyes b'. In the construction shown in Figs. 1 and 2, the eyes are formed in the detachable member by striking up strips of the metal out of the body portion of the same. Obviously, 100 105 110

one or more eyes may be provided for each outer end of the coils, and in the construction illustrated in Fig. 2, one of the eyes marked b^4 is disposed centrally on the clip 5 in position for the end of the spring to pass therethrough and through the eye b' .

The detachable member may be differently formed and arranged and in Fig. 3 I have illustrated a modified form in which 10 such member partakes of the form of a sliding block B' dovetailed in the brush back A' and arranged to slide longitudinally of such brush back. Eyes b^5 on the sliding block serve to engage the outer ends of the coils. 15 This block is held in the brush back against relative movement in suitable manner, as by means of a set screw b^6 .

The flexible connection between the brush head and its handle which is one feature of 20 my invention, adds greatly to the utility of the brush and the ease with which the same is operated. Furthermore, the spring coils serve to distribute the necessary strain throughout its entire length, thereby greatly 25 lessening the liability to breakage.

I claim:

1. The combination of a brush head, a handle therefor, and coiled spring means arranged transversely of and intersecting 30 the axis of the handle and forming the sole operative connection between the head and handle, the intermediate portion of said spring means being secured to the handle and the ends thereof to the head whereby 35 the head is permitted a substantial universal movement with respect to the handle.

2. The combination of a brush-head, a handle therefor, and a pair of coiled spring sections arranged end to end in axial alinement 40 and each having its ends connected respectively with the brush-head and the handle in fixed relationship therewith, said spring sections forming a flexible and the operative connection between the head and handle.

3. The combination of a brush-head, a handle therefor, and a pair of coiled spring sections arranged end to end transversely 45 of the axis of the handle and carried by the brush-head and connected to the handle,

said spring sections acting on said handle to normally hold it perpendicular to the brush-head but arranged to permit such handle to move in a plane longitudinal of the brush-head and also in planes at angles 55 to said longitudinal plane.

4. The combination of a brush back, a handle therefor, a pair of coiled springs arranged end to end with their inner ends twisted together and forming a shank attached to the handle and with their outer ends connected with the back.

5. The combination of a brush back, a brush holding member to which the back is removably secured, a handle, and two 60 coiled springs arranged in axial alinement and transversely of the axis of the handle and attached at their ends respectively to the handle and said member, said springs forming the connection between the handle 65 and said member.

6. The combination of a brush-head, a handle therefor, a pair of coiled springs arranged end to end with their inner adjacent 70 ends secured to the handle and their outer ends operatively connected in fixed manner with the head and forming the sole operative connection between the head and handle.

7. The combination of a brush back, a handle therefor, a member removably secured to the brush-back, and coiled spring means arranged longitudinally of the brush back and transversely of the axis of the handle, said spring means being secured respectively to the handle and to said member.

8. In combination with a brush head, a handle therefor, two intermediate coiled springs arranged end to end and disposed transversely of the axis of the handle, and each connected at its ends respectively with the head and handle and serving as the operative means for connecting the head with the handle.

In witness whereof, I have hereunto signed my name in the presence of two sub- 95 scribing witnesses.

WARREN F. WOLHAUPTER.
